RADIO RECEIVING SYSTEM

John F. Dreyer, Jr., Brooklyn, N. Y., assignor to
Radio Corporation of America, a corporation of
Delaware

Application November 27, 1937, Serial No. 176,779

5 Claims. (Cl. 250—27)

This invention relates in general to radio receiving systems, and more particularly to a circuit organization utilizing a push-pull amplifier stage fed directly from a preceding single tube stage which may function either as an amplifier or as a detector of received signals.

It has been customary in prior practice to use transformer coupling between the output of a preceding single tube amplifier or detector stage and the input to a succeeding push-pull stage, because this form of coupling enables the application of equal voltages to the control grids of the push-pull tubes but in phase opposition. It is also known, in order to avoid the use of transformer coupling, to utilize resistance-capacity coupling, and for obtaining the necessary phase opposition on the push-pull grids there is employed an auxiliary tube known as a phase reversing tube. A circuit embodying the last named suggestion is disclosed in the Gorton United States Patent No. 1,654,075.

It is one of the main objects of the present invention to provide an improved circuit arrangement wherein not only is the use of transformer coupling avoided, but the phase reversing tube of the Gorton patent is also dispensed with in the coupling of a single tube stage to a push-pull amplifier stage.

Another object of the invention is to provide a simplified circuit arrangement that will be efficient in operation and inexpensive to manufacture.

Other objects and advantages of the invention will become apparent to those skilled in the art as the description thereof proceeds. For a better understanding of the invention however, reference is made to the following specification taken in connection with the accompanying drawing which illustrates a circuit embodying the invention.

Referring to the drawing, the circuit is shown to comprise a first tube D which is provided with a cathode C, an anode A, and between said electrodes are interposed a plurality of grid electrodes, marked 1, 2, 3, 4, and 5. Grid 1 serves as the space charge grid and substantially limits the total current emitted from the cathode and prevents the voltage variations of grid 2 from substantially changing this current value, and by reason thereof the tube is inherently balanced in so far as cathode variations are concerned. Grids 2 and 4 are tied together within the tube envelope and serve as auxiliary anodes; grid 3 is the signal control grid, and grid 5 acts as a screen grid. A tube such as thus far described is shown

in the copending application of W. J. O'Brien, Serial No. 759,327, filed December 27, 1934, and assigned to the same assignee as the present application. In that application it is explained that the tube exhibits negative transconductance from the signal control grid toward the grid (or auxiliary anode) interposed between cathode and signal grid as well as a positive transconductance toward the anode. As further explained in said copending application, the object of providing the negative transconductance grid is to effect substantial compensation for the inherent capacity existing in the input grid to cathode circuit whereby all frequencies within a comparatively wide range may be amplified with substantial uniformity. According to the present invention however, advantage is taken of the fact that with respect to the control grid the tube has an auxiliary grid-like electrode or anode which exhibits a negative transconductance, which grid-like electrode together with the regular anode A are utilized as output electrodes.

It was found however, that the regular output anode of the tube operated with the characteristic of a tetrode, i. e., high mu, high plate impedance, whereas the auxiliary grid-like anode exhibited a rather low negative mu. In order that the tube may be efficiently adapted for the purpose intended it is necessary that the transconductances be substantially equal but opposite in sense. In order that the auxiliary grid-like anode may operate to produce a higher amplification factor and a higher impedance to substantially simulate the characteristic of the regular anode, the additional screen S is interposed between the control grid 3 and the grid 2. The screen S has impressed on it a suitable positive potential and may conveniently be connected to the lead 16 which supplies potential to the screen grid 5.

An input circuit 10 is connected between the signal control grid 3 and cathode C. The usual biasing resistance 11 and by-pass condenser 12 are connected in the lead to the cathode C for impressing a suitable initial negative bias on the control grid. A load resistor 13 has one end connected to the anode A and its other end connected to the double grid 2—4. A source of voltage supply 14 such as a battery or the like, has its negative terminal connected to the cathode and its positive terminal connected through the lead 15 to the mid-point of the resistor 13. The screen grid 5 has impressed on it a potential lower than that impressed on anode A and grids 2—4, by means of the lead 16 to an intermediate

point on the source 14. The space charge grid 1 is shown connected directly to cathode, but if desired this grid may be given a slightly negative or a slightly positive potential with respect to 5 the cathode.

The push-pull tubes P and P' are of the pentode type, each containing a cathode C', signal control grid 1', screen grid 2', suppressor grid 3', and anode A'. The signal grid 1' of tube P is 10 connected to the anode side of resistor 13 through the coupling condenser 17, and the signal grid 1' of tube P' is connected through a similar coupling condenser 17 to the double screen side of the resistor 13. A grid leak resistor 18 is 15 connected between each signal grid 1' and ground, and resistor 19 and by-pass condenser 20 constitute the usual biasing network for the signal grids. An output transformer 21 is connected in the anode or output circuits of the push-pull tubes P and P', and the connection 22 from the 20 source 14 to the mid-tap of the transformer primary supplies D. C. operating potential to the anodes A' of the tubes. The same connection also furnishes suitable operating potential to the 25 screen grids 2', 2' of the tubes.

The tube D may be caused to operate either as a detector or as an amplifier. When operating as a detector the push-pull stage will be the power amplifier stage feeding into a utilization 30 means such as the loudspeaker of the receiver. However, when operating as an amplifier the detected signals from a preceding detector tube are fed to the input circuit 10, the tube D serving as a first stage of audio, and the push-pull 35 stage coupled thereto will then operate as the second or final amplifier stage. In either case, there will appear at the terminals of the load resistor 13 potentials of equal value which will vary with the signal but in phase opposition. 40 The potentials so developed across the resistor 13 are then fed to the signal grids through the respective capacity-resistance networks 17-18 to the grids 1', 1' of the push-pull tubes P and P' which operate in the conventional manner. 45 While the invention has been disclosed in a particular form it is to be understood that it is capable of embodiment in other forms without departing from the spirit and/or scope of the appended claims.

50 What I claim is:

1. In a receiving circuit, the combination of a vacuum tube having a cathode, a signal control grid, a plate and an additional grid interposed between cathode and the signal grid, suitable potentials impressed on said electrodes whereby said control grid exhibits a negative transconductance to said additional grid and a positive transconductance to said plate, an auxiliary grid interposed between the signal grid and the additional 55 grid for substantially equalizing said transconductances, an impedance connected between the plate and the additional grid for utilizing the effect of the substantially equal and opposite transconductances, a pair of push-pull tubes, 60 and a resistance-capacity combination coupling the opposite ends of said impedance to the input electrodes of said push-pull tubes.

2. A receiving circuit comprising a first tube provided with a cathode, an anode and a plurality of interposed grid electrodes, a signal input circuit connected between one of said grids

and the cathode, a load resistor connected between the anode and one of the other grid electrodes, a source of space current for said tube connected between cathode and the mid-point of said resistor, whereby said anode and grid to 5 which the load resistor is connected have substantially equal potentials impressed thereon, another of said interposed grids which is adjacent to the control grid having impressed thereon a potential lower than that of the anode, a push-pull 10 amplifier stage fed from said first tube, and means connecting the signal grids of the push-pull tubes to the opposite ends of said resistor.

3. A receiving circuit comprising a tube provided with a cathode, an anode and a plurality 15 of interposed grid electrodes one of which is a signal control grid, means for biasing said control grid whereby the tube will operate as a biased detector, a signal input circuit connected between said control grid and cathode, a load resistor 20 connected between the anode and one of the other grid electrodes, a source of space current for said detector tube connected between cathode and the mid-point of said resistor, whereby said anode and grid to which the load resistor is connected have substantially equal potentials impressed thereon, another of said interposed grids which is adjacent to the control grid having impressed thereon a potential lower than that of the anode, a push-pull amplifier stage fed from 30 said detector tube, and means including resistance and capacity connecting the grid to cathode circuits of the push-pull tubes to the opposite ends of said resistor.

4. In a receiving circuit, the combination of 35 a vacuum tube having a cathode, a signal control grid, a plate and first, second and third grids interposed between cathode and signal grid, a connection from the first grid to the cathode whereby said grid is maintained at cathode potential, substantially equal positive potentials impressed on the second grid and on the plate, and a lower positive potential impressed on the third grid, an impedance connected between said second grid and plate, a pair of vacuum tubes connected in push-pull relation, and a resistance-capacity combination coupling the opposite ends 40 of said impedance to the input electrodes of said push-pull tubes.

5. In a receiving circuit, the combination of a 50 vacuum tube having a cathode, a grid-anode, a signal control grid and a plate-anode arranged in the order named, substantially equal positive potentials impressed on said grid-anode and plate-anode whereby said control grid exhibits a 55 negative transconductance to said grid-anode and a positive transconductance to said plate-anode, which transconductances are unequal, and means for substantially equalizing said transconductances comprising an auxiliary grid interposed 60 between the signal grid and the grid-anode and having impressed thereon a positive potential lower than that of the anodes, an impedance connected between the anodes for utilizing the effect of the substantially equal and opposite 65 transconductances, a pair of push-pull tubes, and a resistance-capacity combination coupling the opposite ends of said impedance to the input electrodes of said push-pull tubes.
